UNITED STATES PATENT OFFICE.

HARRIS W. KLINE, OF SELLS STATION, PENNSYLVANIA.

MAIL-POUCH CRANE.

No. 874,210.

Specification of Letters Patent.

Patented Dec. 17, 1907.

Application filed September 13, 1907. Serial No. 392,732.

To all whom it may concern:

Be it known that I, HARRIS W. KLINE, a citizen of the United States, residing at Sells Station, in the county of Adams and State of Pennsylvania, have invented new and useful Improvements in Mail-Pouch Cranes, of which the following is a specification.

This invention relates to mail pouch cranes and one of the principal objects of the same is to provide a crane which will hold a pouch in position to be caught by the car hook and which will be reliable in action.

Another object of the invention is to provide a crane for mail pouches which will work smoothly and evenly and which will be reliable and efficient for its purpose and in which very slight friction is created between the pivoted parts and their supports.

These and other objects may be attained by means of the construction illustrated in the accompanying drawing, in which:—

Figure 1 is a perspective view of a mail pouch crane made in accordance with my invention and showing a mail pouch connected thereto in position to be caught by the car hook. Fig. 2 is a side elevation of the crane made on an enlarged scale with the mail bag detached. Fig. 3 is a transverse sectional view on the line 3—3 of Fig. 2, looking in the direction indicated by the arrow. Fig. 4 is a vertical section on the line 4—4 of Fig. 2 looking in the direction indicated by the arrow therein.

Referring to the drawings for a more specific description of my invention, the numeral 1 designates an upright or standard adapted to be placed in the ground at a point near the railway and provided with steps 2 and a platform 3 to facilitate the placing of mail pouches in the crane. At the upper end of the upright or post 1 is an angular arm 4. Rising from the arm 4 is a bracket 5 and formed upon said bracket is a curved cam or support 6, the lower surface 7 of which is upwardly curved from a central point toward the opposite ends thereof. Pivoted in the outer end of the arm 4 and projecting above the same is a bifurcated bearing 8 and pivoted in said bearing is the upper pouch supporting arm 9, said arm being pivoted at 10 in the bearing. The rear end of the arm 9 is curved upon its upper surface as at 11, Fig. 4, and is adapted to bear upon the surface 7 of the cam 6. At the outer end of the arm 9 a jaw 12 is provided, said jaw having a groove 13 therein and pivoted between the upwardly

projecting lugs 14 on a pin 15 is a movable jaw 16 provided with a handle 17 and a spring 18 to hold the jaw 16 normally closed.

An adjustable arm 9^a is provided with a metal strap or stirrup 19 which passes around the post 1 at a point where said post is recessed, as at 20. To hold the arm 9^a in adjusted position, a cam lever 21 provided with an eccentric head 22 is pivoted upon a bolt 23 extending through said head and into the arm 9^a. The post or upright 1 is curved on its inner side as at 24 for the head 22. Depending from the arm 9^a is a bracket 25 and formed upon said bracket is a pair of spaced cam keepers 26, the space between said keepers being curved downwardly from opposite sides of the bracket 25. Pivoted in and depending from the outer end of the arm 9^a is a bifurcated bearing 8^a which is similar in construction to the bearing 8, already described. Pivoted in the bifurcated bearing at 27 is the lower pouch supporting arm 28, the rear end of which is disposed between the cams 26 when in position to support a pouch. The outer end of the arm 28 is provided with a rigid jaw 29 having a curved portion 30. Lugs 31 are formed on the arm 28 and pivoted between these lugs on the bolt 32 is a jaw 33 also provided with a groove or curved portion 34. A handle 35 formed on the movable jaw member has connected to it a spring 36 which bears against the arm 28 to normally hold the two jaws in contact.

A mail pouch 37 provided with loops 38 at 90 opposite ends thereof and rings 39 connected to said loops is mounted between the arms 9 and 28, said rings being connected between the rigid and movable jaws 16 and 12 and 29 and 33, as shown in Fig. 1.

The operation of my invention may be briefly described as follows:—When the mail pouch 37 is held in position as shown in Fig. 1 with the rear ends of the arms 9 and 28 disposed centrally to the cams 6 and 26, a very slight force against the bag or pouch in the center thereof will swing the arms 9 and 28 laterally upon their pivots *a* and owing to the formation of the cams 6 and 26, the outer ends of the arms will gradually move one toward the other. When the car hook engages the pouch it will swing the arm laterally and the rings 39 will be readily withdrawn from between the stationary and movable jaws against the tension of the springs 18 and 36.

From the foregoing it will be obvious that a mail pouch supported in the manner de-

scribed can not readily become entangled and dropped when engaged by the car hook. When the arms are swung laterally the pouch is merely supported by the upper ring 39 until the arm 9 passes out from under the cam 6 at which time the bag or pouch will be thrown into the mail car.

Many changes may be made in the detail construction of my mail pouch crane without departing from the spirit and scope of the invention as defined in the annexed claims.

Having thus described the invention, what is claimed as new, is:—

1. A mail pouch crane comprising a standard or post, mail pouch supporting arms pivotally supported upon said post curved cams for engaging the inner ends of said arms and means for supporting a mail pouch upon the outer ends of said arms.
2. A mail pouch crane comprising a standard, an arm projecting at one side of said standard, a bracket on said arm, a curved cam on said bracket, a mail pouch supporting arm pivotally connected to said standard with the rear end of said supporting arm engaging said curved cam, means for supporting a mail pouch on the outer end of said supporting arm, an arm adjustably connected to said standard, a bracket connected to said arm, said bracket carrying two curved cams, a pouch supporting arm pivoted to said adjustable arm with the rear end of said supporting arm disposed between said cams, and means upon the outer end of said supporting arm for engaging a ring on the mail pouch.

3. In a mail pouch crane the combination of a standard, curved cams, pivoted pouch supporting arms engaging said cams, and means for adjusting one of said supporting arms toward and from the other.

4. In a mail pouch crane, a standard, a pouch supporting arm pivoted upon said standard, a curved cam for normally supporting said arm in a horizontal position and means for engaging the lower end of the pouch.

5. In a mail pouch crane, the combination of a standard, a pouch supporting arm pivoted upon said standard, a cam for normally supporting said arm in a horizontal position, an adjustable arm, a pouch supporting arm pivoted thereto and a pair of curved cams between which the end of said supporting arm is disposed.

6. In a mail pouch crane, the combination of a standard, a pouch supporting arm pivoted upon said standard, means for holding said arm in a horizontal position, an adjustable arm, means for holding said arm in adjusted position on said standard, a pouch supporting arm pivoted to said adjustable arm and means for normally holding the said arm in a horizontal position and means for supporting a pouch upon the outer end of said pouch supporting arms.

In testimony whereof I affix my signature in presence of two witnesses.

HARRIS W. KLINE.
